SYSTEM FOR ENERGIZING SPACE DIS-
CHARGE DEVICESBenjamin F. Miessner, Short Hills, N. J., assignor,
by mesne assignments, to Radio Corporation of
America, New York, N. Y., a corporation of
DelawareApplication May 3, 1929, Serial No. 360,045
Renewed October 22, 1931

20 Claims. (Cl. 179—171)

My invention relates to energizing multiple electrode vacuum tubes and like space discharge devices for operation from unsteady sources of current energy so as to limit, control or neutralize the effects of the unsteady current energizing, and in particular to avoid hum production in systems employing such tubes for amplifying sound reproducing currents; radio broadcast receivers and electrical phonographic reproducers in particular being contemplated.

My present invention has for a particular object hum elimination or control with the aid of an additional electrode over the usual three electrode vacuum tube construction, such as the four electrode tube commonly termed "shielded grid" type now promising to enter into more general use.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

Other objects and features of my present invention will be apparent from the following description and discussion in connection with the figures of the accompanying drawing in which like reference characters designate like elements so far as possible in the several figures.

Figs. 1, 2 and 3 diagrammatically illustrate the shielded grid type of tube and amplifier circuits in a variety of associations with a system for energizing the electrodes from an unsteady source of current energy arranged to employ the shielding grid or fourth element as an aid in hum production control.

In each of the figures the tube VT is shown with the conventional form of construction comprising an electron emissive cathode K indirectly heated by a heating wire H energized by alternating current from a transformer T₁, grid G, plate P, and shielding grid G' interposed between grid and plate. The plate electrodes are shown energized from a pulsating source of potential S, an alternating current rectifier for example, through the conventional filter system shown as condensers C₁ and C₂ spanning one inductive element L. Grid bias potential is indicated as obtained in the conventional manner of passing the plate circuit current through a resistance R shunted by a signal current by-pass condenser C₃. Each

of the systems are shown to have signal input and output circuits conventionally including input transformers T and output transformers T'.

In Fig. 1 the shielding grid G' is shown connected to a point intermediate a resistance R₁ across the filter output selected to provide the usual degree of positive potential for this grid element for the desired sort of operation, and since usually very little current flow is wanted in this auxiliary grid connection the resistance of R₁ can ordinarily be given a large value to avoid undue current drain on the filter system for developing the needed potential.

While the development of grid bias potential across resistance R by flow therethrough of the pulsating plate circuit current introduces a pulsating potential component on the grid acting to annul pulsations in the plate circuit current, yet these grid pulsations are not large enough to obtain complete annulling, and are usually further reduced by the general practice of employing a signal current by-pass condenser C₃ to reduce signal degeneration and distortion.

To make up for this incomplete annulling of plate current pulsations, or no annulling if a separate source of steady grid biasing potential is used, I introduce into the shielding grid connection a pulsating component of the same character as that applied to the plate electrode, as by coupling a winding S in this connection to the inductive element L in the filter system, or any other equivalent way of extracting from the source a desired pulsating component. By choosing the polarity and magnitude of this extracted component I can bring to bear a desired annulling effect on the plate pulsations through controlled pulsations on the shielding grid, and thereby control hum to any desired degree, or avoid it, without interfering in any derogatory way with signal current amplification or other normal function of the tube and its circuits.

In Fig. 2 I determine the positive bias of shielding grid G' by a series drop of potential through resistance R'₁ instead of the potentiometer arrangement R₁ of Fig. 1. The condenser G₄ may supplement the coupling of coil S to coil L to determine the degree of pulsations introduced on the shielding grid for hum control.

In Fig. 3 I show one common practice of connecting a signal current by-pass condenser from the plate circuit direct to cathode to reduce signal current degeneration and distortion by lessening the amount of signal current common to the grid and plate circuits in grid bias producing resistance R. Such a connection increases the

- amount of fluctuating component of the plate circuit current that passes through resistance R , and with capacity of condenser C_5 sufficiently large to permit of effective audio frequency signal current by-passing by fluctuating component developed in resistance R and transferred to the grid will exceed that necessary for annulling the plate circuit pulsations. In this case there is no necessity for phase reversal of the pulsations introduced into the shielding grid connection as the phase of the pulsations by the direct connection through resistance R' , is right to annul the over-annulling effect of the grid G . The degree of annulling pulsation on the shielding grid can be controlled by choice of condenser C^4 .
- Having fully described my invention I wish it understood that no limitations other than those imposed by the appended claims are intended by reason of the limited choice of adaptations thereof employed herein for descriptive and explanatory purposes, the invention being one of wide application readily apparent to those acquainted with the art.
- I claim:
1. An amplifier system including a vacuum tube having a cathode, control grid, anode and an anode shield grid electrode, input and output signal current circuits, connections for energizing said control grid and anode electrodes from the some source of unidirectional pulsating current, a connection for energizing said anode shield grid electrode, and means for impressing upon said last named connection pulsations from said source opposed in effect within said tube to the resultant effect of said pulsating energizing of said control grid and anode electrodes.
  2. An amplifier system including a vacuum tube having a cathode, control grid, anode and an anode shield grid electrode, input and output signal current circuits, connections for energizing said anode electrode from a source of unidirectional pulsating current, a connection for energizing said shield grid electrode independently of said control grid electrode, and means for impressing upon said last named connection pulsations from said source opposed in effect within said tube to the effect of said pulsating energizing of said anode electrode.
  3. An amplifier system including an electron discharge tube having a cathode, control grid, anode and an anode screen grid electrode, input and output signal current circuits, connections for energizing said anode electrode from a source of unidirectional pulsating current, a connection for energizing said screen grid electrode independently of said control grid electrode, and means for impressing upon said last named connection pulsations from said source opposed in effect within said tube to the effect of said pulsating energizing of said anode electrode, said means consisting of a path including a resistance connected across said source, and a connection between said screen grid electrode and said resistance.
  4. An amplifier system including a thermionic tube having a cathode, control grid, anode and an anode screen grid electrode, input and output signal current circuits, connections for energizing said anode electrode and said control grid from a source of unidirectional pulsating current, a connection for energizing said screen grid electrode independently of said control grid electrode, and means for impressing upon said last named connection pulsations from said source opposed in effect within said tube to the effect

of said pulsating energizing of said anode electrode, said means consisting of a resistance and a condenser connected in series across said source and a connection between said screen grid electrode and said resistance.

5. An amplifier system including a space discharge tube having a cathode, control grid, anode and an anode screen grid electrode, input and output signal current circuits, connections for energizing said anode electrode from a source of unidirectional pulsating current, a resistance connection between the positive terminal of said source and said screen electrode whereby the potential of said electrode is controlled, and means between said resistance and said electrode for impressing upon said screen grid electrode pulsations from said source opposed in effect within said tube to the effect of said pulsating energizing of said control grid and anode electrodes.

6. An amplifier system including a vacuum tube having a cathode, control grid, anode and an anode screen grid electrode, input and output signal current circuits, connections for energizing said anode electrode from a source of unidirectional pulsating current, a resistance connection between the positive terminal of said source and said screen electrode whereby the potential of said electrode is controlled, a condenser series connected between said resistance and the negative terminal of said source, and means between said resistance and said electrode for impressing upon said screen grid electrode pulsations from said source opposed in effect within said tube to the effect of said pulsating energizing of said control grid and anode electrodes.

7. An amplifier system including a vacuum tube having a cathode, control grid, anode and an anode screen grid electrode, input and output signal current circuits, connections for energizing said anode electrode from a source of unidirectional pulsating current, a resistance connection between the positive terminal of said source and said screen electrode whereby the potential of said electrode is controlled, a transformer the primary of which is series connected between said source and said anode electrode, the secondary of said transformer being connected between said screen grid electrode and said resistance, said transformer being poled to impress pulsations from said source upon said screen electrode, said impressed pulsations being opposed in effect within said tube to the effect of said pulsating energizing of said control grid and anode electrodes.

8. An amplifier system including a vacuum tube having a cathode, control grid, anode and an anode screen grid electrode, input and output signal current circuits, connections for energizing said anode electrode from a source of unidirectional pulsating current, a resistance connection between the positive terminal of said source and said auxiliary electrode whereby the potential of said electrode is controlled, a condenser connected between said resistance and the negative terminal of said source, a transformer the primary of which is series connected between said source and one of the electrodes of said tube, the secondary of said transformer being connected between said screen grid electrode and said resistance, said transformer being poled to impress pulsations from said source upon said screen electrode, said impressed pulsations being opposed in effect within said tube to the effect

effect of said pulsating energizing of said control grid and anode electrodes.

9. A method of operating an electron discharge tube provided with a cathode, control electrode, anode, and an anode screen electrode which consists in heating the cathode to provide a stream of electrons in the tube, energizing said anode and control electrode with a pulsating uni-directional current, biasing said screen electrode positive with respect to said cathode, and impressing upon said screen electrode a pulsating potential component of such polarity and magnitude with respect to the anode energizing pulsations that the latter are effectively controlled.

10. A method of operating an electron discharge tube provided with a cathode, control electrode, anode, and an anode screen electrode which consists in heating the cathode to provide a stream of electrons in the tube, energizing said anode and control electrode with a pulsating uni-directional current, biasing said screen electrode positive with respect to said cathode, and impressing upon said screen electrode a pulsating potential component of such polarity and magnitude with respect to the anode energizing pulsations that the latter are effectively controlled, and controlling the polarity and magnitude of said impressed component.

11. A method of operating an electron discharge tube provided with a cathode, control electrode, anode and an anode screen electrode, which consists in energizing the cathode to provide a stream of electrons in the tube, energizing said anode and control electrode with a pulsating uni-directional current, biasing said screen electrode positive with respect to said cathode, and impressing upon said screen electrode a pulsating potential component of such polarity and magnitude with respect to undesired energizing pulsations of either the control electrode or anode that such undesired pulsations are effectively controlled.

12. A method of operating an electron discharge tube provided with a cathode, anode, and at least two cold electrodes disposed between the cathode and anode, which consists in heating the cathode to provide a stream of electrons in the tube, energizing the anode with a pulsating uni-directional current, biasing one of the cold electrodes negatively with respect to the cathode, biasing the remaining cold electrode positive with respect to the cathode, and impressing upon one of said cold electrodes a pulsating potential component of such polarity and magnitude as to effectively control the occurrence of undesired energizing pulsations in the anode circuit of said tube.

13. A method of operating an electron discharge tube provided with a cathode, anode, and at least two cold electrodes disposed between the cathode and anode, which consists in heating the cathode to provide a stream of electrons in the tube, energizing the anode with a pulsating uni-directional current, biasing one of the cold electrodes negatively with respect to the cathode, with a pulsating uni-directional current, biasing the remaining cold electrode positive with respect to the cathode, and impressing upon one of said cold electrodes a pulsating potential component of such polarity and magnitude as to effectively control the occurrence of undesired energizing pulsations in the anode circuit of said tube.

14. A method of operating an electron dis-

charge tube provided with a cathode, anode, and at least two cold electrodes disposed between the cathode and anode, which consists in heating the cathode to provide a stream of electrons in the tube, energizing the anode with a pulsating uni-directional current, biasing one of the cold electrodes negatively with respect to the cathode, biasing the remaining cold electrode positive with respect to the cathode, but less positive than the anode, and impressing upon one of said cold electrodes a pulsating potential component of such polarity and magnitude as to effectively control the occurrence of undesired energizing pulsations in the anode circuit of said tube.

15. A method of operating an electron discharge tube provided with a cathode, anode, and at least two cold electrodes disposed between the cathode and anode, which consists in heating the cathode to provide a stream of electrons in the tube, energizing the anode with a pulsating uni-directional current, biasing one of the cold electrodes negatively with respect to the cathode, biasing the remaining cold electrode positive with respect to the cathode, and impressing upon one of said cold electrodes a pulsating potential component of such polarity and magnitude as to effectively control the occurrence of undesired energizing pulsations in the anode circuit of said tube.

16. A method of operating an electron discharge tube provided with a cathode, anode, and at least two cold electrodes disposed between the cathode and anode, which consists in heating the cathode to provide a stream of electrons in the tube, energizing the anode with a pulsating uni-directional current, biasing one of the cold electrodes negatively with respect to the cathode, with a uni-directional current including a pulsating component of such polarity and magnitude as to over-annul anode energizing pulsations, biasing the remaining cold electrode positive with respect to the cathode, and impressing upon the remaining cold electrode a pulsating potential component of such polarity and magnitude as to effectively control the occurrence of undesired energizing pulsations in the anode circuit of said tube.

17. An amplifier system including an electron discharge tube having a cathode, control, grid, anode and screen grid, input and output signal current circuits, connections for energizing said anode-electrode from a source of uni-directional pulsating current, a resistance connection between the positive terminal of said source and said screen grid whereby the potential of said screen grid is controlled, a condenser series connected between said resistance and the negative terminal of said source, a grid bias resistor connected between the control grid and the cathode, an audio frequency by-pass condenser connected between said anode and the positive terminal of said grid bias resistor, said screen grid being connected to said first mentioned resistance in such a manner that pulsations from said source are impressed upon said screen grid in such phase and magnitude as to oppose the effect within said tube of energizing pulsations on said control grid.

18. A method of operating an electron discharge tube provided with a cathode, anode, and at least two cold electrodes disposed between the cathode and anode, which consists in heating the cathode to provide a stream of electrons in the tube, energizing the anode with a pulsating uni-

- directional current, biasing one of the cold electrodes negatively with respect to the cathode, biasing the remaining cold electrode positive with respect to the cathode, and impressing upon both 5 of said cold electrodes pulsating potential components of such polarity and magnitude as to effectively control the occurrence of undesired energizing pulsations in the anode circuit of said tube.
- 10 19. In a power supply system for electron tubes, an electron tube having a cathode, anode, grid and shielding grid, a source of pulsating direct current for energizing said anode, a source of pulsating direct current for energizing said shielding grid, and a current source for energizing said cathode, said source for energizing said shielding grid being connected to said shielding grid and to the circuit of said cathode, the pulsations applied to said shielding grid being of magnitude 15 and phase for neutralizing in the circuit of said anode the pulsations of the potential directly applied by said source for energizing said anode, whereby a smooth continuous anode current is produced.
20. In a power supply system for electron tubes, an electron tube having a cathode, anode, grid and shielding grid, a source of pulsating direct current for energizing said anode, a current source for energizing said cathode, a source for energizing said shielding grid, an anode circuit connecting said anode to said source for energizing said anode, a shielding grid circuit connecting said shielding grid to the circuit of said cathode through said source for energizing said 10 shielding grid, a coupling circuit coupled to said anode circuit and to said shielding grid circuit for impressing pulsations in said anode circuit upon said shielding grid circuit, and phase adjusting means for varying the phase of the pulsations impressed upon said shielding grid in desired relation, whereby the effect upon the current in said anode circuit of the pulsations impressed upon said shielding grid neutralizes the pulsations in potential directly impressed upon 15 said anode from said source for energizing said anode and a smooth continuous anode current is produced. 20
